UNITED STATES PATENT OFFICE.

LOUIS A. CORNELIUS, OF GRAND RAPIDS, MICHIGAN.

HOLDER FOR TUMBLERS OR DRINKING-CUPS.

1,098,483.

Specification of Letters Patent. Patented June 2, 1914.

Application filed March 29, 1913. Serial No. 757,524.

To all whom it may concern:

Be it known that I, LOUIS A. CORNELIUS, a citizen of the United States, residing at Grand Rapids, in the county of Kent and State of Michigan, have invented new and useful Improvements in Holders for Tumblers or Drinking-Cups, of which the following is a specification.

My present invention relates to holders for tumblers or drinking cups, and its objects are to provide a device of that character which shall be simple and economical in construction, and which may be readily adjusted to tumblers of different sizes and which may be securely held in any such adjusted positions. These and other objects appearing hereinafter are attained by, and my invention finds a preferable embodiment in, the holder hereinafter described and illustrated by the accompanying drawings, in which:

Figure 1 is a side view of my holder; Fig. 2 is a vertical section thereof on line A—B of Fig. 1; Fig. 3 is a top plan view 25 of the same; and Fig. 4 is a vertical section of certain parts, enlarged, on line A—B of Fig. 1, illustrating the contact points of the parts when clamped together.

A suitable support 1, attached, as to a wall surface in any suitable manner as by screws passing through the orifices 2, carries a pair of holding members 3 adjustable toward and away from each other to accommodate tumblers of different sizes. These holding members are provided with horizontally-extending mutually engaging bars 4 and 5, respectively, semi-circular in cross-section and the straight side vertical, as particularly shown in Fig. 4. These bars, having been manually adjusted to accommodate the desired tumbler, are secured in such adjusted position by horizontally-extending clamp-members 6 and 7 having grooves 8, correspondingly located in the adjacent sides of the clamp members, and semi-circular in cross section as shown in said figure. The circle defined by the cross-section of the grooves is of less diameter than that defined by the cross-section of the bars, so that, as particularly shown in Fig. 4, when

the clamp members 6 and 7 are pressed toward each other by the screw 9 which passes through both and is threaded in the support 1, the contact points of each bar with the clamp members are intermediate the vertical and horizontal diameters of the bar's cross-section, thus insuring a close contact at such points, and also pressing the bars into mutual engagement. Furthermore, it will be seen that owing to the resilience of the bars, they are, by this construction, forced into close frictional contact, along their entire engaging length, with both clamp members and with each other as well, whereby these bars are securely held in their adjustment.

The head 10 of the support is squared, as shown, to engage projections 11 on the under clamp member 7 so that the holding members are held from turning movement when the screw clamps the bars: but, the screw being loosened, the holding members may be turned a quarter way around and reclamped on the head, as desired.

The holding members are preferably of wire, bent to form an arc shaped portion 12 to receive the tumbler, downwardly extending portions 13 and the bar positions 4 or 5.

Not confining myself to details of construction shown or described, I claim:

1. In a holder for tumblers, clamp members having corresponding grooves, and holding members adapted to engage opposite sides of a tumbler and having bars adapted to be clamped together in the grooves and between the clamp members, the contacting surfaces of the clamp members and the bars being oblique to the direction of clamping movement.

2. In a holder for tumblers, a support having a squared head, and clamp members, one having a seat adapted to receive the squared head, attaching means adapted to detachably fasten said members to the head, and holding members adapted to hold a tumbler and to be clamped between the clamp members.

3. In a holder for tumblers, clamp members having corresponding grooves, and holding members adapted to engage oppo-

site sides of a tumbler and having bars adapted to be clamped together in the grooves and between the clamp members, the contacting surfaces of the clamp members and the bars being oblique to the direction of clamping movement, and a screw adapted to operate the clamping members.

In testimony whereof I have hereunto set my hand in presence of two subscribing witnesses.

LOUIS A. CORNELIUS.

Witnesses:

MARION A. THOMPSON,
CYRUS W. RICE.
